[57] CLAIM

The ornamental design for a security workstation enclosure, as shown and described.

DESCRIPTION

FIG. 1 is a perspective view showing a top, front and left side of a security workstation enclosure embodying my new design;

FIG. 2 is a front elevational view of the security workstation enclosure of FIG. 1;

FIG. 3 is a left side elevational view of the security workstation enclosure of FIG. 1;

FIG. 4 is a top plan view of the security workstation enclosure of FIG. 1;

FIG. 5 is a rear elevational view of the security workstation enclosure of FIG. 1; and,

FIG. 6 is a bottom plan view of the security workstation enclosure of FIG. 1.

FIG.1
